(57) **CLAIM**

The ornamental design for a stuffed animal with prosthetic, as shown and described.

DESCRIPTION

FIG. 1 is a perspective view of the toy prosthetic;

FIG. 2 is a front elevation view thereof;

FIG. 3 is a bottom view thereof;

FIG. 4 is a right side view thereof; and,

FIG. 5 is a left side view thereof.

The broken line showing of the stuffed animal is for illustrative purposes only, and forms no part of the claimed design.
